POWER LIMITING METHOD AND APPARATUS

Filed May 29, 1922

Inventor:
Oliver E. Buckley
by C. C. Sprague, Atty.

UNITED STATES PATENT OFFICE.

OLIVER E. BUCKLEY, OF MAPLEWOOD, NEW JERSEY, ASSIGNOR TO WESTERN ELECTRIC COMPANY, INCORPORATED, OF NEW YORK, N. Y., A CORPORATION OF NEW YORK.

POWER-LIMITING METHOD AND APPARATUS.

Application filed May 29, 1922. Serial No. 564,428.

This invention relates to magnetic power limiting devices and methods.

The principal object of the invention is to provide new and improved method and apparatus for limiting the power delivered from an electric circuit to a translating device. Another object of the invention is to provide for comparatively undistorted transmission to a translating device of a variable 10 electric current of low power, and to shield the translating device from the effect of a current of higher power. Another object of the invention is to guard the user of a telephone receiver against shocks that might be 15 caused by excessive currents in the circuit to the receiver, but to facilitate the undistorted transmission of normal voice currents. These and other objects of the invention will become apparent on consideration of a specific example which has been chosen for presentation in the following specification. This embodiment of the invention will now be described with the understanding that the definition of the invention is given in the 20 appended claims.

Referring to the drawings, Fig. 1 is a diagram of a telephone receiver and circuit embodying the invention, and Fig. 2 is a diagram showing magnetic relations that will 30 be referred to in explaining the principle of the invention, and Fig. 3 is an enlarged view of the portion of the curves of Fig. 2 near the origin.

Referring to Fig. 1, the line circuit 11 transmits voice currents from apparatus 12 to the transformer or repeating coil designated generally as 13. This transformer 13 has separate windings, a primary 14 and a secondary 15, on the same core 16. The core 40 material is permalloy, a composition of nickel and iron in certain proportions and heat-treated in a certain manner, which will be discussed presently. In circuit with the secondary winding 15 is the receiver 17.

The nature of the core material 16 and the quantity of it used in the transformer are such that the repeating coil 13 faithfully reproduces normal voice currents. But when excessive currents come over the line 50 11, as for example, if it should become crossed with a power line, then the power transmitting capacity of the transformer 13 is so limited that no excessive current will be induced in the secondary 15, notwithstanding

the excessive current rush in the primary 14. 55 Accordingly, a listener at the receiver 17 will have his ear protected against "acoustic shock" and will not be exposed to the danger of injury that might otherwise come to him by the use of a transformer at 13 with high 60 capacity for transmitting power from the primary to the secondary.

A suitable material for the core 16 is permalloy which may be conveniently used either in the form of wire or thin sheets to 65 accomplish the results indicated in the foregoing description. A suitable variety of permalloy is a composition of nickel and iron in the respective proportions of 78½% nickel and 21½% iron. Good commercial 70 grades of these ingredients are fused together in an induction furnace, molded into the convenient form of a thick bar or rod and worked down by any of the standard 75 methods of working metals of this general character to the form of wire or sheets, whichever is desired. The particular size of wire or thickness of sheets to be used depends, of course, on the particular requirements of the coil or transformer in which 80 this material is to be used as the core. It is desirable to have the wire sufficiently fine or the sheets sufficiently thin to minimize losses which would otherwise be introduced by eddy currents and also to secure the full 85 effect of the high permeability of permalloy by causing the lines of magnetic induction to penetrate through the whole cross-section of the magnetic material, which they would not do if the magnetic material were in a 90 thick form, owing to the well-known phenomenon of shielding which occurs at high frequencies and which, on account of the high permeability of permalloy, is very 95 marked in this material. A convenient diameter of the wire for coils or transformers to be used at voice frequencies is about 0.010 100 inch. A convenient thickness of sheets is about 0.003 inch.

The wire or sheet having been worked 100 down to the proper size is next to be heat treated. If the material is used in the form of wire, the procedure is to wind the wire into the form desired for the core of the transformer. This may conveniently be 105 of the form of a ring. The wire in this form should be carefully bound together so that in ordinary handling subsequent to the

heat treating process it will not suffer unnecessary mechanical strain. Having been wound and bound in the proper shape, the core is next heated to a temperature of about 850 degrees C. and held at that temperature for a few minutes to insure that all the wire is at the same temperature. The core should then be cooled slowly to a temperature of 600 degrees C. and from that temperature should be cooled more rapidly at a definite rate which will depend on the size of material to be used and the form in which it is used. This can be easily determined by trials. A convenient means of securing the desired rate of cooling is to quickly withdraw the core from the furnace when it has reached the temperature of 600 degrees C., and place it in a blast of air which is controlled to secure the desired rate of cooling.

If sheets are to be used they should be first cut or stamped to the desired form, but previous to assembling them to form the core of the coil they may be heat treated separately in a manner similar to that described for the wire core, and later bound together. This treatment may be used in the case of the sheet, since the sheets can be handled and bound together without seriously straining the material. The permeability of permalloy depends very greatly on the condition of mechanical strain. Its initial permeability at zero magnetizing force may be reduced from values in the neighborhood of 6,000 down to values of the order of 600 by the mere act of stretching the material. It is, therefore, desirable to carefully avoid strains in the finished core.

While 78½% and 21½% have been mentioned as giving the proportion of the ingredients of nickel and iron to be employed in making up the improved magnetic material, it will be understood that the proportion may deviate considerably from these figures and that it may be desirable for other reasons to add other ingredients than nickel and iron, such, for instance, as chromium, which may be used to increase the resistivity, and consequently decrease the eddy current loss in the material.

The process of making the transformer which is shown schematically in Fig. 1 having been explained, the principle of action which enables the benefits of the invention to be secured will now be explained. It is a property of permalloy that its permeability at very low magnetizing forces is extraordinarily high, being of the order of 6,000 for zero magnetizing force, whereas the corresponding value for the best grades of iron is only about 300. The value of the permeability at zero force is obtained by determining a series of values for exceedingly low forces, say of the order of .01

to .05 gauss. The results plot linearly and may be extrapolated back to the value for H=0.

Other important qualities of this composition for the purpose of my invention are its comparatively low value of magnetization when magnetically saturated and the relatively low magnetizing force required to saturate it. The maximum magnetization of permalloy is about 10,500 lines per square cm. and it is nearly saturated with a magnetizing force of 1 gauss.

These properties of permalloy are made use of in the following manner. The high permeability at low magnetizing forces is made useful by designing and constructing a transformer with a core of permalloy of relatively small cross-section. Since the initial permeability is about twenty times that of iron, approximately the same efficiency at low voltages, so far as limits imposed by magnetic properties are concerned, may be secured with a small permalloy core as with an iron core of twenty times the cross-section. Now, by virtue of the small cross-section and small value of magnetization when saturated, the latter being only one-half that for iron, the transformer with the permalloy core is only able to transfer about one-fortieth (or less depending upon the mode of application of the electromotive force) the energy from the primary to the secondary which can be transferred by the iron core, when both are operated with high voltages which give high values of magnetic field strength. Thus the transformer with the permalloy core is fully as efficient as that with the iron core for low voltages but much less efficient for high voltages, and accordingly serves as an energy limiting device for high voltages.

The invention may be better understood by referring to Figs. 2 and 3, which show R-H diagrams P and I for permalloy and for a good grade of iron, respectively, the latter material being about the best magnetic material available before permalloy was known. The initial permeability is given by the slope of the tangent line OT at the origin, and as shown on the diagram this is very much steeper than the corresponding tangent OT' for the iron curve. However, as the diagram shows, the magnetization of the iron is greater than that of the permalloy for field strengths greater than about 1.6 gauss and the ultimate magnetization (not shown on the figure which only goes to 4.0 gauss) is about twice as great for iron as for permalloy.

Let the ratio of the trigonometric tangents of the angles XOT and XOT' be N. The curves P and I in Figs. 2 and 3 have relation to a unit volume of the magnetic material in each case. Coordinate values of H and B mean that if H units of mag-

netizing force are applied, then B units of magnetic flux will be developed per unit cross-section. Let us deal with a smaller cross-section of permalloy such that its area 5 is $\frac{1}{N}$ unit. This will give the curve P_1 whose ordinates are $\frac{1}{N}$ times those of the solid line curve for permalloy, but it will 10 make the initial ratio of total magnetic flux ϕ to magnetizing force H the same for the permalloy as for the iron. Hence for low magnetizing forces (ampere turns), the small core of permalloy will carry the same 15 flux and give the same induction in a secondary winding as the larger core of iron with N times the cross-section. However, the maximum flux that the permalloy will carry will be far less than for iron, nearly 20 $2N$ times less, both because of the smaller cross section and because of the less flux carrying capacity per unit cross-section at saturation.

25 The application of the foregoing discussion will readily become apparent. What ever the cross-section of iron that would be necessary for the core of transformer 13 , the core of permalloy, according to this in- 30 vention, is made about $\frac{1}{N}$ times that cross-

section. This transformer with the small 35 permalloy core will then be equivalent to the larger iron core transformer for the lowest magnetizing forces, and will be more efficient than the iron core transformer up to field strengths of about 0.4 to 0.6 gauss where the permalloy curve P_1 intersects the iron curve I . Beyond this point, for field 40 strengths greater than 0.4 to 0.6 gauss the iron core transformer would be much more efficient than the one having the permalloy core. Thus for the normal operating range, which is, by proper design of the transformer, at less than 0.4 to 0.6 gauss, the 45 permalloy core transformer is fully as efficient as the iron core transformer, but for higher magnetizing forces, where for purposes of protection low efficiency is desired, the permalloy core transformer is very much less 50 efficient than the iron core transformer and is accordingly incapable of transferring so much energy to the secondary circuit.

55 This improved current limiting device has the advantage over a fuse or automatic circuit breaker in that the latter must first experience a current of excessive energy before it will act and limit the further trans-

mission of energy, whereas the device of this invention is incapable at any stage of transmitting an excessive energy. The rush 60 of energy that produces operation of a fuse or automatic circuit breaker may do much damage before the device interrupts the current.

The invention claimed is:

65 1. Means to protect the user of a telephone receiver against acoustic shock, consisting of an interposed transformer in the voice current circuit, with separate windings and with a small core of higher initial permeability than iron and lower value of magnetization at saturation.

70 2. In a telephone system, means for preventing acoustic shock, comprising a magnetic current limiting device having a core of magnetic alloy consisting chiefly of nickel and iron and having higher initial permeability than iron and lower magnetization at saturation.

75 3. In a signaling system, a receiving instrument and means for preventing abnormally large currents from reaching said instrument comprising current limiting means having a magnetic core of an alloy consisting chiefly of nickel and iron, said core having higher initial permeability than iron and lower magnetization at saturation.

80 4. In a telephone system, means for preventing acoustic shock, comprising a magnetic current limiting device having a core of alloy consisting chiefly of nickel and iron and in which the nickel component predominates, said core having higher initial permeability than iron and lower magnetization at saturation.

85 5. A magnetic power limiting device comprising a coil and a core therefor of magnetic alloy consisting chiefly of nickel and iron, said core having a higher permeability than iron for magnetizing forces of a few 90 tenths of a gauss and having lower magnetization than iron at saturation.

95 6. In a telephone system, means for preventing acoustic shock comprising a transformer inserted between the line and the receiving instrument and having a core of an alloy comprising the magnetic elements iron and nickel, the nickel component being within a few percent of $78\frac{1}{2}\%$ of the magnetic element content.

100 In witness whereof, I hereunto subscribe my name this 26th day of May A. D., 1922.

OLIVER E. BUCKLEY.
